(57) **CLAIM**

The ornamental design for a display with a projector, as shown and described.

DESCRIPTION

FIG. 1 is a perspective view of front, right and top of a display with a projector according to an embodiment showing my new design;

FIG. 2 is a perspective view of rear, right and top thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines represent the portions of the design that form no part of the claim.
